His Attorney.

UNITED STATES PATENT OFFICE.

ERNEST H. JACOBS, OF CHICAGO, ILLINOIS, ASSIGNOR TO GENERAL ELECTRIC COMPANY, A CORPORATION OF NEW YORK.

ELECTRIC SWITCH.

1,347,779.

Specification of Letters Patent.

Patented July 27, 1920.

Application filed July 30, 1917. Serial No. 183,436.

To all whom it may concern:

Be it known that I, ERNEST H. JACOBS, a citizen of the United States, residing at Chicago, in the county of Cook, State of Illinois, have invented certain new and useful Improvements in Electric Switches, of which the following is a specification.

My invention relates to electric switches and has for its object to provide an electric switch in which the operating member or handle is movable in one direction to trip the switch and in the opposite direction to reset the switch and is adapted to be automatically returned to initial position free of the switch mechanism from either switch closing or switch tripping position.

The novel features which I believe to be characteristic of my invention will be indicated in the claims appended hereto while the features of construction and mode of operation will be understood from the following description taken in connection with the accompanying drawing which shows in perspective a switch embodying the features of my invention.

In the drawing, a switch embodying the features of my invention is shown comprising fixed contacts 1 and 2 and a movable or bridging contact member 3 coöperating therewith to open and close the circuit through the switch. The bridging contact 3 is carried by a longitudinally movable rod 4 which is carried by an actuating arm 5 to which rod 4 is pivotally secured near one end thereof. The arm 5 is biased to circuit opening position by a biasing means or spring 6 which also acts to accelerate the movement of the arm 5 and rod 4 in switch opening direction. The arm 5 is supported at its opposite end by a bearing member 7 preferably integral therewith and movable upon a shaft 8.

For restraining or locking the actuating arm 5 in switch closing position against the bias of spring 6, a latching or restraining means is provided comprising a latching member 9 pivotally mounted on a separate shaft and carrying a pin 10 which is adapted to engage a latching recess 11 on the arm 5. The latching member 9 is normally biased to latching position and is movable to releasing position either automatically or at will in response to the hand operation of the switch.

For automatically moving the latching

member 9 to releasing position, an electro-responsive means or solenoid 12 is provided which has a plunger 13 adapted when raised to strike the end of the latch 9 and move it to releasing position whereupon the switch is automatically tripped open. For tripping the switch at will or in response to the hand operation of the switch, a tripping means is provided comprising a member 14 movable on the shaft 8 and carrying a tripping arm 15. Member 14 also carries a lug 16 which coöperates with the pin 10 of latch 9 to move it from the recess 11 and permit the actuating arm 5 to move to circuit opening position. The bearing member 7 also carries a resetting means or arm 17 which is operative to move the bearing member 7 and actuating arm 5 from switch opening to switch closing position and to simultaneously return the member 14 by means of the lug 18 from switch tripping position to its initial position.

The operating means for the switch consists of a handle member 19 mounted on a shaft 20 upon which is also mounted an independently operative operating member 21 consisting of an arm curved in configuration and biased by means of a spring 22 to normally occupy a position free from the remaining mechanism for the switch and acting to automatically return the operating arm to initial position from either tripping or resetting positions. The tripping arm 15 and the resetting arm 17 are arranged to extend into the path of movement of operating arm 21, the arm 21 being located between the tripping and resetting arms and independent therefrom.

A movement of the operating arm 21 in an upward direction caused by a movement of the handle 19 to the right engages the tripping arm 15 to trip the switch and a movement of the handle 19 in the opposite direction carries the arm 21 into engagement with the resetting arm 17 to reset the switch, the arm 21 automatically returning to its initial position free from both said arms by the spring 22 when the handle 19 is released, whereby the switch is adapted to be automatically tripped independent of the handle.

The operation of my switch may be described as follows. In the position shown in the drawing, the switch is in closed position and the operating arm 21 is in its

- initial position free from the remaining mechanism of the switch and maintained in this position by the spring 22. The handle 19 is accordingly in its initial position.
- 5 When the switch is automatically tripped by the electroresponsive means 12, the plunger 13 engages the latch 9 and raises it with pin 10 to release the actuating arm 5 and permit it to move accelerated by the spring 6 into switch opening position. This movement of the actuating arm 5 rotates bearing member 7 and moves the resetting arm 17 in the direction of the operating arm 21 but not into engagement with the same. This 15 automatic opening of the switch does not therefore disturb the operating mechanism for the switch and the handle 19 occupies the same position whether the switch is opened or closed. In order to trip the switch 20 by hand, the handle 19 is moved to the right in tripping direction carrying operating arm 21 into engagement with the tripping arm 15 and causing a rotation of member 14 to carry the lug 16 into engagement with the pin 10 raising the latch 9 and releasing the actuating arm 5. The movement of member 14 to tripping position is limited by the lug 18 carried on member 7. Upon release of the handle 19, the handle and the operating 30 arm 21 automatically return to initial position by the force exerted by spring 22.
- In order to reset the switch, the handle 19 is moved to the left or in resetting direction to carry operating arm 21 into engagement with resetting arm 17. The movement of the resetting arm 17 by the operating arm 21 actuates the bearing member 7 and carries actuating arm 5 into circuit closing position, the pin 10 of latch 9 falling by 35 gravity, into the latching recess 11 of arm 5 and restraining it in switch closing position. If the switch has been automatically tripped, the movement of the biasing member 7 also causes its lug 18 to carry the member 14 and with it the tripping arm 15 and

lug 16 to their initial position. Upon release of the handle 19, it automatically returns to initial position free from the resetting arm 17 and into a position such that the movement of the resetting arm 17 as the 50 switch is automatically tripped takes place independent of the handle.

What I claim as new and desire to secure by Letters Patent of the United States, is:

1. An electric switch comprising fixed and 55 movable contacts, an actuating arm for controlling said movable contact, a latching member biased to engage said arm and restrain it in switch closing position, an independent tripping member movable to engage 60 said latching member and move it to releasing position, an independent resetting member for moving said actuating arm from switch opening to switch closing position, and an independently mounted operating 65 arm intermediate said tripping and resetting members and movable to engage either of said members but biased free of both said members.

2. An electric switch comprising fixed and movable coöperating contacts, an actuating shaft, an actuating arm carrying said movable contact mounted on said shaft and biased to switch opening position, a latching member biased to engage said arm and restrain it in switch closing position, a tripping member carried by said shaft for moving said latching member to releasing position, a resetting member carried by said shaft for moving said actuator arm from switch opening to closing position, an independently movable operating handle, and an operating arm controlled by said handle and biased to assume a position intermediate said tripping and resetting members and movable to either engage said tripping or resetting members.

In witness whereof I have hereunto set my hand this 26th day of July, 1917.

ERNEST H. JACOBS.
